UNITED STATES PATENT OFFICE.

ALEC E. FINGERHUT, OF CLEVELAND, OHIO.

TONSILLOTOME.

Application filed December 27, 1926. Serial No. 157,044.

This invention as indicated relates to an improvement in surgical instruments and particularly in a device known as a tonsillotome. The instrument is intended especially for the removal of the tonsils although its use is not intended to be restricted solely to the tissues referred to but may be applied, within the scope of the claims, to the removal of other diseased portions of the body. 5 In the operation of removing diseased tonsils, it is desirable to compress the pillars or supporting tissues to prevent subsequent hemorrhage from the associated blood vessels, and, while thus holding such attaching 10 members firmly, to sever the diseased tonsil by an operation of the instrument readily carried on by the same gripping movement which compressed the pillars. In devices heretofore used for tonsillotomy, separate 15 means for clamping the pillars and for severing the diseased tonsils are provided and these means are often controlled with difficulty and necessitate the operator changing his position at the critical time of the 20 operation.

The present invention has in view the obviating of the difficulties referred to and the provision of an instrument which by a simple gripping movement will serve to clamp and 25 lock the diseased tonsil firmly within the aperture of the device and which by a simple, readily accessible adjustment within the reach of the thumb of the operator will permit a further movement of the actuating 30 lever to be made which will carry the cutting blade through the adjacent tissue.

In addition to the features just mentioned, the device is provided with a release which is instantaneous in action and requires no 40 careful adjustment to become immediately effective.

To the accomplishment of the foregoing and related ends, said invention, then consists of the means hereinafter fully described 45 and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

Fig. 1 is a side elevation of an instrument embodying the principles of my invention; 55 Fig. 2 is a central vertical sectional view showing the upper portion of said instru-

ment; Fig. 3 is an enlarged vertical sectional view showing the trigger mechanism with its upper end in its forward position of adjustment; Fig. 4 is a horizontal sectional view taken immediately above the clamping bar; Fig. 5 is a top plan view of the clamping bar; Fig. 6 is a top plan view of the cutting bar; Fig. 7 is an enlarged detail view partly in section showing the receptacle for the severed tissue; Fig. 8 is an end elevation of the structure shown in Fig. 7; and Fig. 9 is a fragmentary plan view of the forward end of the instrument showing a modified form of opening.

As is clearly shown in the drawing, the instrument comprises a body member 1 having a rearwardly extending handle portion 2, formed integrally therewith. Said handle portion is shaped at its lower end to fit the curvature of the hand of the user and a rearward extension 3 is formed to engage above the thumb of the operator. The upper portion of the body member terminates in a horizontal extending upper edge 4 provided with lateral flanges 5, and formed with a smooth top surface. The body member is open centrally to its upper edge to receive the upper end of an operating lever presently to be described.

An elongated frame member 6 is adapted to be engaged upon the upper surface of the body member being suitably recessed to fit over the margins thereof. Said frame member is provided with an elongated central opening of somewhat greater diameter at its projecting forward portion than its rearward portion which fits upon the body member.

The forward end 7 of the frame member is adapted to form one portion of the clamping device, the other portion comprising a clamping bar 8, which with a cutting bar or knife 9, is adapted to be slidingly supported on the upper surface of the body member.

The clamping bar, as shown in Fig. 5, comprises a metal plate of slightly larger diameter adjacent the forward end 11 than over its main body portion 12. The bar is provided with a threaded extension stem 13 firmly secured to its rearward end by any suitable means such as brazing or welding or by means of a driving fit. At a point slightly in advance of the point of juncture of the stem with the plate portion 105 of the screw-threaded extension, a slot 14 is provided which may be regarded as

formed of two parallel spaced slots with an intermediate slot joining the two at their rearward portions so as to present an irregular opening having a rearwardly projecting lug 15 at its forward end, and a rearwardly extending slot 16 at its rearward end. The clamping bar referred to is adapted to fit within the frame member which as stated is recessed on its under side, thus providing a portion to overlie the top surface of the body member, with marginal flanges to engage over the lateral flanges of the body member and hold said frame in place. The frame thus provides a slideway for the clamping bar and knife and its forward edge provides the abutment toward which said slideable members move to effect their several functions. The rearward end of the frame is enlarged and joined with a portion 17 of cylindrical cross-section in order to provide a suitable housing for a split nut control device 18 for the clamping bar. The split nut portion of the apparatus is mounted on a cap 21 having a circumferential flange 22 adapted to fit over the cylindrical rearward end of the frame. Centrally of the cap a cylindrical extension 23 is rigidly secured which is centrally apertured to receive threaded extension of the clamping bar and which is transversely slotted to provide working space for the screw-threaded jaws 24 of the split nut. The jaws of the split nut at their forward edges are provided with outwardly extending cam members 25 and at their opposite ends are provided with similar cam members 26. The two parts of the split nut are pivoted to the cap extension adjacent their central portions. The length of the split nut members is slightly greater than that of a reduced cylindrical opening 27 formed in the frame which accommodates the forward end of the cap extension. Thus when the split nut is engaged with the screw threads of the stem, the cam extensions thereon will slide within the cylindrical opening. When, however, the cap member is moved forwardly toward the rearward end of the frame, the rearward cam members on the split nut will be brought into contact with the rearward faces of the cylindrical opening and will positively move the threaded forward or gripping portion of the split nut away from the threaded portion of the stem member, permitting the smooth cut away rearward portions of the split nut to overlie the threaded stem. In order to normally hold the split nut in engagement with the threads of the clamping bar, a spring 31 is provided in the space between the flange on the cap and an enlargement 32 at the base of the cylindrical extension, said spring at its opposite ends being engaged against the rearward face 33 of the cylindrical portion of the frame. Thus the cap is normally pressed rearwardly

and the forward cam members of the split nut hold it in engagement with the stem. By rotating the cap the clamping bar may be moved to any desired position, thus changing the size of the opening through the forward end of the instrument.

In addition to the clamping bar, the frame, as stated, is adapted to provide a guideway for the knife. The knife structure is substantially similar in outline with that of the clamping bar having a broad forward portion 34 and a narrow rearward portion 35. Instead of having a screw-threaded stem extension, however, the knife is formed without any extension whatsoever, but is provided adjacent its rearward end with a slot 36 somewhat similar in outline to the slot formed through the rearward end of the clamping bar. Said slot, however, is to be distinguished from the slot in the clamping bar in that its rearwardly extending tongue 37 is of lesser depth than that in the clamping bar and its rearward extension slot 38 is of greater depth. The purpose of the difference in the openings in the respective clamping end cutting bars will be presently described. The forward portion of the knife is provided with a keen cutting edge 39.

A housing 41 of sheet metal open adjacent its rearward under side and having an aperture 42 corresponding with the desired operating space of the instrument, is provided to form the outer casing for the upper mechanism of the instrument. The shape of the opening may be rectangular as shown in Fig. 4, or may be rectangular as to three sides and curved at its forward edge which is the preferred form of construction, and shown in Fig. 9. Where the aperture has a curved forward edge, it is necessary to have the frame member and forward end of the casing 43 shaped similarly as well as to provide a curved forward edge 44 on the cutting blade and clamping bar.

The housing, as stated, is slotted on its under side adjacent its rearward end to permit the same to be moved backwardly over the lateral flanges on the body member. A pair of ears 45 is provided adjacent the rearward end of the housing which are suitably apertured to receive a securing bolt 46. The bolt may be formed with an enlarged head (not shown) to serve as a stud or finger grip to be engaged by the forefinger of the operator in pressing the cap forwardly with the thumb. It will be placed on the right or left hand side of the instrument according to whether the surgeon uses his right or left hand.

The rearward portion 47 of the housing is made cylindrical in shape so as to engage over the cylindrical portion of the frame. The forward end of the housing may be provided on its under side with an extension

which may be formed integrally therewith in the shape of a receptacle 48 which will receive the severed tissue and prevent the same from falling into the throat and causing strangulation.

The trigger portion of the apparatus will now be described. The handle portion of the device as has been indicated comprises a rearward extension formed rigidly with the body member, which supports the clamping bar and sliding knife. As stated, it is provided with a rearwardly projecting finger which serves as an abutment for the thumb of the instrument engaging hand of the operator so that a firm grip may be had when the trigger is to be operated. The trigger portion of the device comprises a lever 51 provided with an open loop 52 adapted preferably to receive four fingers of normal size and having a pair of spaced projecting bars or fingers 53 at its upper end. A pivot pin 54 for the trigger is engaged through suitable openings in the lever and body member. The extension fingers at the upper end 25 of the trigger are spaced from each other a distance equal to the spacing of the outer portions of the slots in the clamping bar and knife heretofore described. An intermediate finger 55 is provided between those first described and is pivoted centrally on the first pin of the lever. Said intermediate finger is provided with a segmental enlargement 56 at its intermediate point with a notch 57 having a flat face at its forward side and a curved rearward face. Said notch is adapted to be engaged when set in proper position by a portion of the semi-cylindrical central portion 61 of a locking bar 62 engaged through the body portion of the lever 51. Said pin at its outer end is provided with an operating lever 63 which terminates in a button or thumb piece 64 of any desired shape. Said thumb piece carries on its under side a detent (not shown) which is adapted to ride into slight depressions 65 at either end of an arcuate groove 66 defining its path of movement on the handle adjacent the point of support of the trigger. Thus when the control lever is positioned in its upper adjustment, the intermediate finger or extension on the trigger will be locked in slightly forward position with respect to its adjacent fingers. When so locked the trigger when moved will force the central finger against the rearwardly extending lug of the clamping plate and knife to move the same forwardly. When the lugs are so positioned, the knife edge will be spaced and securely locked approximately one-eighth of an inch to the rear of the front edge of the clamping bar and there, therefore, will be no cutting action whatsoever. While the fingers are adjusted as stated, the lateral fingers will be engaged in the respective lateral slot portions of the openings through the clamp-

ing bar and knife respectively, said fingers engaging the rearward portions of the clamping bar slots and the forward portions of the knife lateral slots.

The lever 51 is normally held with its upper end rearward and its lower end forward by means of a pair of leaf springs 71, 72 interengaging at their upper ends and having their lower ends respectively secured to the inside faces of the handle and lever.

In the position just described, the apparatus is ready to be engaged over a tonsil and moved into clamping engagement with the pillars of the same. The threaded portion of the split nut will be opened by the forward movement of the clamping bar and will lock as soon as the pressure is released. Therefore the clamping bar may be forced into locking engagement with the tissues which it compresses. When the desired clamping action has been obtained, the surgeon is ready to move the knife to sever the diseased tonsil and this is accomplished by moving the thumb piece downwardly to its extreme limit of motion which will serve to turn the pivoted bar through approximately an angle of 90° and thus releasing the central finger from locking relation to the lateral fingers. When so released, the central finger will have no positive movement against the rearwardly projecting lugs of either the knife or clamping bar. The lateral fingers, however, will engage the forward edges of the lateral slots through the knife and will move the same forwardly so as to effectively sever the tonsil from its supporting tissue. Thus the action of moving the clamping bar against the tonsil and the moving of the knife to sever the tonsil so clamped is accomplished by successive movement in a single direction. After severing the tonsil where the instrument is provided with a receptacle as heretofore described, the severed tissue will be securely held within the receptacle and no danger of strangulation occurs. It is therefore possible to maintain the clamping engagement with the severed tissues for a brief period of time after the operation has been completed. This has the advantage of sealing the edges of the severed tissue and reducing the usual hemorrhage which takes place in such operations to a minimum. After the compression upon the adjacent tissues has proceeded for the additional time desired by the operating surgeon, the cap 120 is forced forwardly so as to spread the two sections of the split nut and release the clamping bar. The latter will be moved freely backward as soon as the members of the split nut spread apart and release the 125 screw-threaded stem.

Other modes of applying the principle of my invention may be employed instead of the one explained, change being made as regards the mechanism herein disclosed, pro-

vided the means stated by any of the following claims or the equivalent of such stated means be employed.

I therefore particularly point out and distinctly claim as my invention:

1. An article of the character described, having in combination a handle portion and a laterally extending section, an aperture in said lateral extending section adapted to be engaged over an object to be amputated, means within said laterally extending portion for clamping said object, means associated with said clamping means for severing said object, and unitary means associated with said handle for selectively operating said clamping and severing means in combination or said severing means independently by successive movement in a single direction.
2. An article of the character described having in combination an elongated member provided with clamping means and tissue severing means and means for selectively operating said clamping and severing means together or one of said means separately by successive movement in a single direction.
3. An article of the character described having in combination an elongated member provided with clamping means and tissue severing means, means for selectively operating said clamping and severing means together or one of said means separately by successive movement in a single direction, and means adjacent said severing means for receiving said severed tissue.
4. An article of the character described having in combination an aperture adapted to engage over the object to be operated upon, a clamping member and a severing member slidably engaged within said apertured member, means for automatically holding said clamping means in locked engagement with the tissues to be severed, means for moving said clamping means forwardly and means for selectively moving said cutting means forwardly independently of said clamping means by successive movement in a single direction.
5. An apparatus of the character described, having in combination a frame, a cutting member and a clamping member asso-

ciated with said frame, a lever for actuating said cutting and clamping members in fixed relation to each other, means associated with said lever for disconnecting said clamping means from said cutting means by successive movement of said lever in a single direction, and permitting the independent operation of said cutting means.

6. An apparatus of the character described, having in combination a frame, a cutting member and a clamping member associated with said frame, a lever for actuating said cutting and clamping members in fixed relation to each other, means associated with said lever for disconnecting said clamping means from said cutting means, and permitting the independent operation of said cutting means by successive movement of said lever in a single direction, and means for releasing said clamping bar from engagement with said locking means.

7. An apparatus of the character described, having in combination a frame, a clamping bar slidably mounted on said frame, a cutting bar slidably mounted on said frame, a lever pivotally mounted on said frame and provided with a plurality of fingers adapted to engage said clamping and cutting bars, a latch to release one of said fingers from said lever permitting the other of said fingers to move independently thereof.

8. An apparatus of the character described, having in combination a frame, a clamping bar slidably mounted on said frame, a cutting bar slidably mounted on said frame, a lever pivotally mounted on said frame and provided with a plurality of fingers adapted to engage said clamping and cutting bars, a latch to release one of said fingers from said lever permitting the other of said fingers to move independently thereof, a screw-threaded member associated with said clamping bar, a split nut associated with said frame adapted to move said clamping bar forwardly and means connected with said split nut for releasing the same from said screw-threaded member.

Signed by me this 9th day of December, 1926.

ALEC E. FINGERHUT.
